CLAIM

(22) Filed: **Aug. 11, 1999**

The ornamental design for a mounting fixture for internal arrangement of a screening device on a window, as shown and described.

(30) **Foreign Application Priority Data**

DESCRIPTION

Feb. 12, 1999 (DK) ..... MA 1999 00182

FIG. 1 is a perspective view from the top, front and right side of a mounting fixture showing my new design;

(51) **LOC (7) Cl.** **08-07**

FIG. 2 is a perspective view from the bottom, rear and right side of the mounting fixture;

(52) **U.S. Cl.** **D8/349**

FIG. 3 is a left side elevational view of the mounting fixture;

(58) **Field of Search** D8/382, 499; 411/38,

FIG. 4 is a top plan view of the mounting fixture;

411/542, 908

FIG. 5 is a right side elevational view of the mounting fixture;

4,228,736 * 10/1973 Hall D8/382

FIG. 6 is an inverted rear elevational view of the mounting fixture;

D. 269,760 * 7/1983 Geney D8/382

FIG. 7 is an inverted front elevational view of the mounting fixture; and,

3,845,927 11/1974 Bratschi .

FIG. 8 is a bottom plan view of the mounting fixture.

4,416,572 * 11/1983 Black 411/38

4,832,551 * 5/1989 Wollar 411/280
